UNITED STATES PATENT OFFICE.

WILLIAM HENRY ALLEN, OF BIRCHFIELDS, BIRMINGHAM, ENGLAND, ASSIGNOR TO
HENRY ERNEST KEATING, OF BIRMINGHAM, ENGLAND.

GARMENT-FASTENER.

1,229,395.

Specification of Letters Patent. Patented June 12, 1917.

Application filed June 24, 1916. Serial No. 105,753.

To all whom it may concern:

Be it known that I, WILLIAM HENRY ALLEN, subject of the King of Great Britain, residing at 24 Hatfield road, Birchfields, Birmingham, in the county of Warwick, England, have invented a new and useful Garment-Fastener; and I do hereby declare the following to be a full, clear, and exact description of the same.

10 This invention has for its object the provision of an improved button fastener for use principally on trousers and similar articles of wearing apparel in which fashion decrees the formation of a central crease down each leg thereof whereby, when not in use, the trousers may be folded in the desired creases and maintained in such position by the improved buttons. These buttons are also applicable for use as a means of attachment for the braces in the usual manner.

15 The improvements according to this invention reside in a button fastener composed of two separate integers, a male and a female, with means in connection with each whereby engagement between the two may be attained when pressed face to face, each integer being so formed as to be capable of use as a means of attachment for the usual braces and adapted, when in use, to be disposed one above each crease on the trouser legs for the purpose of maintaining such members folded in their respective creases when not in use.

20 Referring to the drawings:—

25 Figure 1. illustrates a pair of trousers provided with button fasteners according to this invention.

30 Fig. 2. is a similar view with the trousers folded and the fastener on the point of being mutually engaged.

35 Figs. 3 and 4 represent front elevations of the female and male portions of one form of button and

40 Figs. 5 and 6 sections on the lines 3—3 and 4—4 of Figs. 3 and 4 respectively.

45 Fig. 7 is a vertical section of the male and female portions of a further form of button according to this invention showing the same separated.

50 Fig. 8 a plan of the female portion thereof and

55 Fig. 9 a view similar to Fig. 7 but showing the two portions engaged.

Figs. 10, 11 and 12 are similar views to Figs. 7, 8, and 9 respectively but of a slightly modified form.

60 Similar letters of reference indicate like parts throughout the views.

Referring now to Figs. 1 to 6 the male and female portions are denoted by the letters *a* and *b* respectively.

65 The female portion *b* shown in Figs. 3 and 5 is in the shape of a dish and is stamped from a single piece of metal. The upper edge of this dish is inturned to form a lip *c* which extends completely there-around and forms a protection for a blade spring *d* disposed therebeneath and within the dish.

70 This spring *d* is supported in spaced relation to the base of the dish by projections *e*, which if desired may be substituted for a continuous or split ring, and is formed with a plurality of waves which produce a series of inwardly extending loops *f* each of which project to a slight extent beyond the inner edge of the lip *c*.

75 The base of the dish is formed with the usual centrally disposed protuberance *g* having a series of apertures *h* therein through which the thread or the like is passed when attaching the portion of the button to the garment.

80 The male portion *a*, see Figs. 4 and 6, is similarly constructed from a single piece of metal as the female portion above described, but is of a smaller diameter it being so proportioned as to readily enter the aperture formed by the edge of the lip *c*.

85 Extending around the circumference of this male portion is a rectangular or other shaped groove *i*, which is formed by the spaced beads *j* and *k* extending around the upper and lower edges of the portion *a* respectively.

90 The protuberance *g* in the male portion is disposed opposite to that in the female portion, and in accordance required to be of slightly greater dimensions as will readily be seen from a comparison of the figures.

95 In operation the male portion *a* is pressed into contact with the female portion *b*, with the result that the forward bead *j* forces the loops *f* outward and allows the male portion to be pressed completely home, when the loops *f* spring back again into place and en-

100

105

gage the groove *i* in such position. To dis-
engage the portions the action is repeated
as regards the operation of the spring *d*.

In the example illustrated by Figs. 7 to 9
5 the spring *d* is obviated, the female portion
b being provided instead with a plurality of
radial cuts or slots *l* arranged at equal dis-
tances around its edge.

In construction the body of this female
10 portion is somewhat similar to the example
first described, with this exception that the
outer edge is curved outwardly as at *m*, in-
stead of being inturned as at *c*. Further its
15 sides are bent so as to form a rounded cheek
n internally with which a similar cheek *o*,
on the male portion *a*, is adapted to snugly
engage when the two portions are inter-
locked.

In operation the circumferential cheek *o*,
20 of the male portion, is forced between the
opening in the female portion, the radial
cuts or slots *l* allowing for the necessary ex-
pansion to accommodate the difference in
diameters.

25. The example illustrated in Figs. 10 to 12
differs from that illustrated in Figs. 7 to 9
in that the lip *c*, on the female portion, is
turned inward all around as to point verti-
cally downward, and is shallower than the
30 fellow portion in such previous example.
The male portion is splayed and is formed
all around with a slightly upturned lip, the
outside diameter of which is in excess of
that of the inside diameter of the mouth of
35 the female portion. The method of engage-
ment is similar to the previous example, the

cuts *l* being provided to accommodate the
difference in diameters.

In use the two portions forming the im-
proved button in accordance with this in-
vention are sewn one on each side of the
trousers as seen in Figs. 1 and 2 and di-
rectly, or approximately so, above each leg
crease and thus take the place, in these two
positions, of the usual trouser buttons, which
may be retained for the remaining posi-
tions.

What I claim then is:—

1. In a pair of trousers the combination
of two buttons each adapted for use sepa-
rately for securing the braces, one provided
50 with a male part and the other formed fe-
male so that when the two buttons engage
the trousers are folded along the correct
crease line.

2. In a pair of trousers the combination
of two buttons each adapted for use sepa-
rately for securing the braces, one provided
55 with a male part having an external periph-
eral groove and the other formed female and
having an internal wire spring adapted to
coact with the aforementioned groove so
that when the two buttons are thus engaged
the trousers are folded along the correct
crease line.

In testimony whereof I affix my signature
in presence of two witnesses.

WILLIAM HENRY ALLEN.

Witnesses:

HAROLD J. C. FOULSTER,
JNO. COWPER.
